PROCESS OF WEAVING

Frank W. E. Hoeselbarth, Carlisle, Pa., assignor to C. H. Masland & Sons, Carlisle, Pa., a corporation of Pennsylvania

Application June 19, 1950, Serial No. 168,960

6 Claims. (Cl. 139—39)

The present invention relates to pile carpets which exhibit a plurality of levels of pile in the face, and to methods of weaving the same.

The fabric subject matter of the present application has been embodied in a divisional application, Serial No. 257,006, filed November 19, 1951, for Pile Carpet.

A purpose of the present invention is to produce a pile carpet having in different transverse rows of the same pile warp, wavy uncut pile loops and wavy cut pile tufts, desirably alternating with one another, with or without intervening pile projections of another pile warp.

A further purpose is to weave a pile carpet, applying alternately to the same pile warp, a straight non-cutting wire and a wavy wire having a cutter at the far end, weaving with a closeness of weave in excess of seven wires per inch and preferably between seven and twelve wires per inch, more desirably between eight and ten wires per inch and most desirably between nine and ten wires per inch, whereby when the wavy wire is withdrawn, the required extra pile yarn to permit the high points of the wavy wire to be withdrawn will be only partly supplied by pulling down on the loops formed over the straight wire, and will partially be obtained by springing the yarn and fabric, and after the pile projections are cut by the wavy wire, the spring-back in the yarn and fabric will selectively pull down the tufts formed over the wavy wire and create a wavy effect in such tufts.

A further purpose is to restrict the extent to which the withdrawal of the wavy wire can pull down the adjoining straight wire loops so as to create spring-back which will produce waviness in the wavy wire pile projections.

A further purpose is to produce the alternating wavy transverse rows of cut and uncut pile projections in accordance with the invention in single pile warp velvet carpets, multiple pile warp velvet carpets and Wilton carpets as desired.

A further purpose is to employ straight non-cutting wires which are the same height as the maximum heights of the waves on the wavy wires, so that the maximum heights of the waves on the cut and uncut pile will be the same, and at points across the weave the cut pile tufts will at least partially mask the low wavy portions of the uncut loops, thus effectively blanking out the low uncut loops.

A further purpose is to displace the high points of the waves of the successive wavy wires and correspondingly of the successive pairs of wavy tufts and loops laterally with respect to one another to produce a pattern effect.

Further purposes appear in the specification and in the claims.

In the drawings I have chosen to illustrate a few only of the numerous embodiments in which my invention may appear, selecting the forms shown from the standpoints of convenience in illustration, satisfactory operation and clear demonstration of the principles involved.

Figures 1 to 4 are weave step diagrams showing the successive steps of weaving a velvet pile carpet in accord-

2

ance with the invention, using a single pile warp. The warps are in the plane of the paper.

Figure 5 is a fragmentary perspective of a wire set repeat which may be employed in various weaves of the present invention, the high points of the waves of the wavy wire being at a different height from the straight wire.

Figures 6 to 9 are wire-withdrawal weave diagrams of a weave in accordance with Figures 1 to 4, using wires corresponding to Figure 5 except that the high points of the waves of the wavy wire equal the height of the straight wire, and showing in longitudinal (warpwise) section the steps of withdrawing the two different wires.

Figure 10 is a conventional longitudinal or warpwise section of a completed carpet in accordance with Figures 1 to 4 and Figures 6 to 9.

Figures 11 and 12 are top plan wire diagrams showing the distributions of the high points on the wavy wires laterally across the wire set.

Figure 13 is a fragmentary section of a wavy wire employed in the invention, showing the contour of the wave.

Figure 14 is a face view of a single pile warp velvet carpet conforming to the weave of Figures 1 to 4, and 6 to 9 and 10 and embodying the principles of the invention. This may be regarded as the preferred embodiment.

Figure 15 is a face view of a single pile warp velvet carpet similar to Figure 14, except that the number of wires per inch was less than 7, and the wave in the cut tufts which is very desirable in the present invention is not exhibited. All other conditions are the same in Figures 14 and 15.

Figures 16 to 19 inclusive are views corresponding to Figures 1 to 4 except that two pile warps are used and in accordance with the velvet carpet system.

Figure 20 is a view corresponding to Figure 6, but showing the effect of using two different pile warps as in Figures 16 to 19.

Figure 21 is a view of the weave of Figures 16 to 19, but corresponding to Figure 9.

Figure 22 is a longitudinal fabric sectional diagram corresponding to Figure 10, but showing a weave of Figures 16 to 19.

Figures 23 to 26 are weave step diagrams corresponding to Figures 1 to 4, but showing a Wilton weave applied to the invention.

Figure 27 is a longitudinal sectional view corresponding to Figure 6, but showing the Wilton weave of Figures 23 to 26.

Figure 28 is a view corresponding to Figure 9, but showing the Wilton weave applied to the invention, at a point where pattern change does not occur.

Figure 29 is a view similar to Figure 28 except that it shows a point of pattern change.

Figure 30 is a view corresponding to Figure 10, but showing the Wilton weave applied to the invention.

In the drawings like numerals refer to like parts.

In C. H. Masland, 2nd, U. S. patent application Serial No. 144,764, filed February 17, 1950, for Weaving with Effect from Orientation of High and Low Pile, now abandoned, disclosure is made of weaving carpet with alternate non-cutting straight wires and cutting wavy wires over which the same pile warp is raised. In accordance with the Masland invention, it is disclosed that when a wire set is employed, using alternate straight wires and wavy wires, when the wavy wire is withdrawn from the fabric it tends to pull down the pile projections formed over the straight wire, producing wavy pile projections, and raising the pile projections formed over the wavy wire until they achieve the height of the tops of the waves of the wavy wire. Thus in a loose weave, the result is to form wavy pile projections over the straight wire (by robbing from the pile projections formed over the straight wire after that wire is with-

drawn) and to form straight pile projections over the wavy wire (by raising such pile projections to the maximum height of the waves when the wavy wire is withdrawn).

I have discovered that this effect, however, can be advantageously modified when a very tight weave is employed. In this case the tightness of the weave restricts the extent to which the wavy wire during withdrawal can rob pile from the pile projections formed over the straight wire, and while to some extent the pile required to permit withdrawal of the wavy wire is robbed from the pile projections produced over the straight wire, a substantial amount of pile required to permit withdrawal of the wavy wire is obtained by stretching the pile yarn and distorting or springing the back of the fabric on both sides of the wavy wire. The extent of the stretching the pile yarn and distortion or springing of the back of the fabric depends upon whether the particular pile projection is located at an initial low point or high point on the wavy wire, there being a great deal of stretching and distortion or springing at initial low points on the wavy wire and very little or no stretching and distortion or springing at initial high points on the wavy wire. After the wavy wire has been withdrawn, the pile projections at points where the pile yarn has been stretched and the back of the fabric has been distorted or sprung are pulled down or sprung back to an extent depending upon the extent of stretching, distortion or springing, thus producing wavy pile projections over the wavy wire, and creating a very novel effect.

Thus in accordance with the present invention, when I weave the same pile warp alternately over a straight non-cutting pile wire and a wavy pile wire having a cutter at the far end (remote from the head) I produce a transverse row of wavy uncut pile projections and a transverse row of wavy cut pile projections alternating on the same warp. Where other warps are employed, as in a Wilton weave or in a special multiple pile velvet weave as later explained, the cut warp or warps can exhibit the same effect or some other effect such as low pile, cutting or non-cutting, or a high pile, cutting or non-cutting, straight or wavy.

The most convenient manner of restricting the pull-down of the loops formed over the straight wire when the wavy wire is withdrawn, and thus causing spring-back to impart a wave to the pile tufts formed over the wavy wire is by increasing the closeness of the weave. This can be done very effectively by increasing the number of wires per inch to in excess of seven, and preferably less than twelve, more desirably between eight and ten wires per inch, and most desirably between nine and ten wires per inch. Closeness of weave can also be increased by increasing the number of ends per inch in the warp with a view to causing springback and waviness in the warp. The effect of the invention can be enhanced or varied by varying bulkiness of the pile yarn, adjusting tension of the binder warps, stuffer warps, pile warps and weft, varying the elasticity and thickness of the pile warp ends, and wefts, varying the construction of the carpet, and varying the heights of the wires and the heights of the tops and bottoms of the waves on the wavy wires.

For practical purposes, using any conventional weaving set-up it will be sufficient to keep the number of wires per inch between seven and twelve, in order to get the effect described herein, the pull-down on the uncut loops decreasing and the wave of the cut tufts increasing as the number of wires per inch increases within this range.

These ranges of wires per inch will cause the effect of the invention by restricting pull-down of the loops formed over the straight non-cutting wire by the wavy cutting wire, unless the pitch is too open or the pile yarn is too light.

The following table sets forth for various pitches the

range of wires per inch which produces the spring back effect of the invention, with pile yarns of usual elasticity and of the weights specified:

5	Dents per 27" (pitch)	Wires per inch which produce effect of invention	Pile yarn (yards per ounce)
10	160.	10 to 12	42 or heavier.
	180.	9 to 12	50 or heavier.
	200.	7 to 12	60 or heavier.
	216.	7 to 12	65 or heavier.
	256.	7 to 12	75 or heavier.

- 15 It will of course be evident that the pile yarn should not be thick enough to prevent weaving by causing excessive crowding as well known in the art. The following table lists for a pitch of 200 dents per 27 inches on a velvet carpet weave of the construction shown in Figure 20, the approximate limits of pile yarn thickness which are usually practical from the standpoint of crowding for the various wire densities.

25	Wires per Inch	Limit of thickness of pile yarn in yards per ounce
7.		28
8.		28
9.		45
10.		50
11.		55
12.		60

- 33 The effect in accordance with the invention is enhanced by employing high points on the successive wavy wires which are laterally out of phase with one another according to some pattern or other arrangement.

- 40 Where the top of the wave of the wavy wire is at substantially the same height as the straight wire, the novel effect of the invention is further enhanced by providing points along the transverse rows where the wavy cut pile tufts partially or wholly mask the low wavy uncut pile loops, creating an additional interesting effect on the face of the fabric.

- 45 The invention is applicable to single pile velvet carpet weaves (including tapestry), multiple pile velvet carpet weaves (including tapestry) and Wilton weaves, as well as other pile carpet weaves. The invention can be applied to one or any or all of the pile warps where a plurality of pile warps are employed. Where it is applied to one of several pile warps, there may be transverse rows of pile projections of other characters between the alternate uncut wavy pile loops and cut wavy pile tufts.

- 55 The present invention constitutes a simple and practical way to impart a wavy effect to alternate cut and uncut pile rows, overcoming the difficulty of the prior art in this direction.

- 60 Considering Figures 1 to 4 inclusive, these figures show diagrammatically the four steps of the cycle of a velvet carpet weave by which the process of the invention can be carried out and the weave of the invention can be produced. These figures illustrate a pile warp 40 manipulated by a pile warp heddle 41 and withdrawing pile 65 from a pile warp beam 42 over a whip roll 43. It will be evident that through the present disclosure any tensioning device is conveniently designated as a whip roll, whether it usually be called a whip roll or a jumbo in current practice.

- 70 Stuffer warp 44 is withdrawn from stuffer warp beam 45 over whip roll 46. The stuffer warp is manipulated by stuffer warp heddle 47. It will be evident that if desired the usual practice can be followed of manipulating the stuffer warp by a long slot in the heddle whose eyes carry the pile warp.

Binder warps 48 and 50 are withdrawn from binder warp beam 51 over a whip roll 52 and manipulated by binder warp heddles 53 and 54 respectively. A reed is shown at 55.

Much of the description which is given applies throughout to Figures 1 to 4, 16 to 19 and 23 to 26, and will not be repeated in considering these various figures. The first wire used in each cycle is designated 56 and the second 58, the detail characters of the wires being shown in the views of the weaves themselves.

In the first step shown in Figure 1, pile heddle 41 is fully raised, binder warp heddle 53 and stuffer warp 47 are raised half way and binder warp heddle 54 is lowered, so that a wire 56 is inserted in the shed beneath pile warp 40 and above all other warps, while a shot of weft 57 is inserted in the shed beneath pile warp 40, binder warp 48 and stuffer warp 44 and above binder warp 50. The reed beats up the wire and weft at the end of the first step.

In the second step shown in Figure 2, pile warp heddle 41 is down, binder warp heddles 53 and 54 remain in the previous position, and stuffer warp heddle 47 is down. A shot of weft 57 is taken in the shed beneath binder warp 48 and above all other warps. The reed 55 then beats up the weft to complete the second step.

In the third step as shown in Figure 3, pile warp heddle 41 is raised, binder warp heddle 53 is lowered, binder warp heddle 54 is raised half way, and stuffer warp heddle 47 is raised half way. A wire 58 is inserted in the shed beneath pile warp 40 and above all other warps, while a weft 57 (suggested by a diagrammatic showing of the shuttle) is inserted in the shed beneath pile warp 40, beneath binder warp 50 and beneath stuffer warp 44 and above binder warp 48. The beat of reed 55 on the wire and weft completes the step.

In the fourth step of the cycle shown in Figure 4, pile warp heddle 41 is lowered and the binder warp heddles remain unchanged, while stuffer warp heddle 47 is lowered and a shot of weft is inserted in the shed beneath binder warp 50 and above all other warps. The beat of the reed 55 on the weft completes the step and completes the cycle.

Figure 5 shows in more detail the relationship between the wires 56 and 58 inserted on the cycle of Figures 1 to 4. As shown, wire 56 in this case has a smooth straight "round" or non-cutting top surface 60, while wire 58 in this case has an undulating or wavy top surface 61 and is provided with a cutter 62 conventionally illustrated at the far end (remote from the head). It will be understood that the cutter 62 will be of the usual type provided on a spoon, and the showing made is merely conventional.

As shown in Figure 6, a single pile warp 40 is bound under face wefts 57' and extends over the respective wires 56 and 58. The chain warps 48 and 50 reverse around each pair of wefts consisting of face wefts 57' and back wefts 57''. The stuffer warp 44 passes in front of back wefts 57'' and behind face wefts 57'. As the fabric is woven in Figure 6 before the wires are withdrawn, the pile warp 40 rises over and conforms to the straight upper surface 60 of straight non-cutting wire 56 and conforms to the waves or undulations on the top surface 61 of wavy wire 58.

Figure 7 illustrates in a view similar to Figure 6 the effect of withdrawing the last straight non-cutting wire 56. It will be seen at the left of Figure 7 that pile loops 63 formed over the straight wire remain momentarily in the same position as they were in Figure 6, until the wavy wire is withdrawn.

Figure 8 shows the initial effect of beginning to withdraw the wavy cutting pile wire (in this case 58). Pile projection 64 is pulled up to permit the highest point on the wave of the wire to pass as shown in Figure 8, while

pile loop 63 is pulled down as shown in Figure 8. If the weave is a loose weave as already explained, the amount that pile loop 63 is pulled down in Figure 8 will substantially correspond to the amount that pile projection 64 is pulled up, but if instead the weave is a tight weave (for example in excess of 7 wires per inch) in accordance with the invention, pile loop 63 will be pulled down by an amount less than that which pile projection 64 is pulled up, the difference corresponding to the amount of stretch distortion or spring in the yarn or back of the fabric. Assuming that the weave under discussion is a tight weave, it will be understood that a pile projection initially formed over the wavy wire at a low point 65 (Figure 5) will be pulled up a considerable amount to pass the high points 66 of the wavy wire (Figure 5), but a pile projection initially formed over a comparatively high point 67 on the wavy wire will be pulled up very little. In a tight weave, therefore, there will be great spring developed in a pile projection initially formed over a low point 65 on the wavy wire, and little spring developed in a pile projection initially formed over a comparatively high point 67 on the wavy wire. Correspondingly there will be comparatively great pull down of the pile loop 63 which is adjoining a low point 65 on the wavy wire and comparatively little pull-down of the pile loop 63 which is adjoining a high point on the wavy wire.

Figure 9 illustrates the effect after the wavy wire is fully withdrawn and cutter 62 on the far end of the wavy wire cuts pile projection 64 into pile tufts 68. The pile tufts may have heights as shown at 68 or 68', depending upon the amount of spring back from the spring created in the yarn and fabric, the pile tufts being relatively high as at 68 when there is relatively little spring back and relatively low as at 68' when there is more spring back. Correspondingly as the amount of pull-down of loop 63 will depend on whether adjoining pile projection 64 is at a high point or low point initially on the wavy wire, if pile tuft 68 is high there is usually very little pull-down in pile loop 63 and it will be high, whereas if pile tuft 68' is low, pile loop 63' will usually be lower. In general, however, except at the very high points, the wave in the pile tufts is less pronounced than the wave in the pile loops, so that comparatively high pile tufts will adjoin comparatively low pile loops, notwithstanding that these pile tufts may be lower than some other pile tufts in the transverse pile rows.

This is illustrated in Figure 10 where comparatively high pile tufts 68 adjoin a comparatively high pile loop 63 and lower pile tufts 68' adjoining a still lower pile loop 63'. It will be understood, of course, that the pile height in both the cut tufts and uncut loops varies continuously from side to side in the transverse pile rows.

Very interesting and novel effects can be obtained by offsetting the high points 66 of the wavy wires as shown in top plan in Figure 11. Here the high points conform to a suitable pattern which in the present instance is a chevron 70. In order to suggest that the high points of the wavy wires may conform to any other desired configuration, Figure 12 shows the high points 66 displaced to form a random pattern 71 across the wire set.

The configuration of the wavy wire may vary widely. Figure 13 shows a wavy wire whose wavy surface 61 follows a sine curve. The low points 65 in a particular example were 0.130 inch high, while the high points 66 were 0.290 inch high. The distance between high points 66 along the wire in this example was 1.8 inches and the angle of the curve at the inflection point was approximately 15° in both directions from the high points to the troughs of the curve.

A very interesting and novel effect is obtained when the height of the straight wire is the same as the maximum height of the waves on the wavy wire as shown in Figures 6 to 9 inclusive. In this case the cut pile tufts adjoining the low uncut pile loops partially mask or con-

ceal the loops as shown at 71 in Figure 14 or fully mask them as shown at 72. At other points 73 the pile loops, however, stand out clearly and conform to the wire pattern due to the lateral offsetting of the high points of the adjoining wavy wires.

Figure 14 also shows the wavy effect in the cut pile tufts which is quite pronounced in the fabric and is illustrated in Figure 14 by highlights.

Figure 14 was woven, using wires of the character already described, with a single pile warp of 200 dents in 27 inch width, one pile end per dent, in a velvet carpet weave 8½ wires per inch and 200 pitch.

Figure 15 illustrates the face of a fabric which is identical with that of Figure 14 except that it was woven with 6½ wires per inch, so that the spring back of the fabric which caused the wavy effect in the cut pile in Figure 14 does not exist in Figure 15. Figure 15 shows a wave in the uncut loops, but does not illustrate the wave in the cut pile tufts which is characteristic of the present invention.

Commercial samples embodying the weave of the invention have been successfully woven using a round wire of height of 0.290 inch and a wavy wire varying between 0.216 inch and 0.90 inch, with successive wires per inch in different samples of 7½, 7¾, 8, 8½, 8¾, 9, 9½, 9¾ and 10. There were in each case 200 dents to 27 inches, with one pile end per dent. The distance between high points on the wavy wire was 1.8 inches. In each case a two-ply jute stuffer was employed, and all of the fabrics exhibited the effect shown in Figure 14. All of these fabrics were woven according to the velvet carpet system and using a single pile warp.

A commercial sample has been developed employing a noncutting round wire of height 0.290 inch and a wavy wire having a minimum height in the wave of 0.135 inch and a maximum height in the wave of 0.290 inch, the length on the wavy wire between the high points being 1.8 inches. The width of the chevron effect in the wire set was 2 inches, and the length between the point of one zig-zag and the corresponding point of the next varied in various samples from 2.3 inches to 2.5 inches. A single velvet pile was employed, using one pile end per dent and using 200 dents in a 27 inch width. Several stuffer ends per dent were employed.

Another commercial velvet pile carpet in accordance with the invention employed a round straight wire of 0.220 inch, and a wavy cutting wire varied from 0.135 inch to 0.220 inch. The same spacing between high points was employed and the high points varied in a block configuration 2 inches on one side and 2½ inches on the other side. The same thread-in was employed.

The principles of the invention can be applied to velvet weaves having a plurality of pile warps all ends of which are raised over wires at different points in the cycle in accordance with my copending application Serial No. 167,534, filed June 12, 1950, for Velvet or Tapestry Weave, Loom and Velvet or Tapestry Carpet Fabric, which is incorporated herein by reference. The principles of obtaining pattern effects by variation in thread-ins as explained in that application can be applied if desired with the principles of the present application, using different numbers of ends per dent and using ends-out per dent in combination with ends-in per dent in the different pile warps as there explained.

Figures 16 to 19 inclusive illustrate a weave generally as described in my copending application above referred to, to which the principles of the present invention have been applied. In these figures there are two pile warps 40 and 40', the second pile warp 40' being suitably withdrawn from a beam 42' (intended to be any suitable source of pile warp) over whip roll 43' and manipulated by a pile heddle 41'.

In Figure 16, showing the first step of the velvet weave employing two piles in accordance with my co-

pending application, pile heddle 41' is fully raised, pile heddle 41 is lowered, binder warp heddle 53 is raised half way, binder warp heddle 54 is lowered, and stuffer warp heddle 47 is lowered. A wire 56 is inserted 5 in the shed beneath pile warp 40', and above all other warps, while a shot of weft 57 is inserted in the shed beneath pile warp 40' and binder warp 48, and above binder warp 50, pile warp 40 and stuffer warp 44. The beat of reed 55 on the wire and weft completes the 10 first step.

In the second step shown in Figure 17, pile warp heddle 41', pile warp heddle 41, binder warp heddle 53 and stuffer warp heddle 47 are all raised half way and binder warp heddle 54 is lowered. A shot of weft 57 is taken in the shed above binder warp 50 and beneath all other warps. The reed 55 then beats up the weft to complete the second step.

In the third step shown in Figure 18, pile warp heddle 41 is fully raised, binder warp heddle 54 is raised half way and all other heddles are lowered. A wire 58 is inserted 20 in the shed beneath pile warp 40 and above all other warps. A shot of weft 57 is taken in the shed beneath pile warp 40 and binder warp 50 and above pile warp 40', binder warp 48 and stuffer warp 44. Reed 55 beats up the wire and weft, completing the 25 third step.

In the fourth step shown in Figure 19, pile warp heddles 40 and 40', binder warp heddle 54 and stuffer warp heddle 47 are raised half way, and binder warp heddle 53 is lowered. A shot of weft is taken in the shed above binder warp 48 and beneath all other warps. The beat of reed 55 on the weft completes the fourth step and completes the cycle.

The wires 56 and 58 introduced on the same cycle as 35 shown in Figures 16 to 19 will be straight noncutting pile wires 72 and 73 introduced on one cycle, and wavy cutting pile wires 72' and 73' introduced on the next cycle. All ends of pile warp 40' are alternately raised over a straight noncutting pile wire 72 and wavy pile 40 wire 72' having a cutter at the far end, and all ends of pile warp 40 are alternately raised over a straight noncutting pile wire 73 and a wavy pile wire 73' having a cutter at the far end, as shown in Figure 20.

It will be understood from Figure 20 that the wire 45 repeat consists of wires 72 and 73 which are inserted in the cycle described in Figures 16 to 18 inclusive, and which will desirably be of one type, for example both straight non-cutting, and wires 72' and 73' which are of the other type, in this case wavy and provided with 50 cutters at the far ends. Thus the wire repeat consists in this case of four wires, two of which are inserted on one weaving cycle and the next two on the next weaving cycle. It will be noted however that in the case 55 shown the wires operating on the same warp 40 or 40' are alternately straight non-cutting and wavy cutting, and preferably as shown the high points of the waves on the wavy wires are the same in height as the straight wires so as to obtain the masking effect already described. The high points on the wavy wires are laterally offset in the preferred embodiment according to 60 Figure 11 or 12.

Figure 21 shows the resulting fabric after withdrawal 65 of the wires in Figure 20, so that on each pile warp there are alternately uncut wavy pile loops 63 at one transverse row and cut pile tufts 68 at the next transverse row of the same pile warp (actually on the next cycle). Due to the tightness of the weave (in excess 70 of 7 wires per inch), the spring back occurs to pull down the cut pile tufts 68 and produce a variation in height in the same transverse row or a wavy effect in these cut pile ends (there is also a wavy effect in the pile loops). This is indicated by showing lower pile 75 tufts 68' behind the plane of the paper and a lower pile loop 63' behind the plane of the paper, to suggest the wavy effect in each transverse pile row.

Figure 22 shows in a conventional weave diagram and back wefts the character of the resulting velvet carpet, with wavy pile loops 63 or 63' at one transverse row on a particular pile warp and wavy pile tufts 68 or 68' in the next transverse row on the same pile warp.

While Figures 16 to 21 show the wavy effect in uncut loops and cut tufts on both alternate transverse rows of each of the pile warps, it will be understood that if desired the effect of cut wavy pile tufts and uncut wavy pile loops, desirably with partial masking of the lower loops by the tufts, may be confined to less than all of the pile warps.

Figures 23 to 26 show the weave carried out stepwise on a Wilton loom. Figure 23 shows the first step, with lingoe heddles 41² and 41³ both down, binder warp heddle 54 down, stuffer warp heddle 47 down and binder warp heddle 53 raised half way. A shot of weft 57 is taken in the shed beneath binder warp 48 and above all other warps, and the step is completed by beating up the weft with reed 55.

The second Wilton weave step is shown in Figure 24, in which lingoe heddles 41² are raised, lingoe heddles 41³ are raised half way, binder warp heddle 54 and stuffer warp heddle 47 are raised half way and binder warp heddle 53 is lowered. A wire 56 is inserted in the shed beneath the ends of pile warp 40 raised by lingoe heddles 41² and above all other warps. A shot of weft is taken in the shed above binder warp 48 and beneath all other warps. The beat of reed 55 on the wire and weft completes the step.

In the third step shown in Figure 25, binder warp heddle 54 is raised half way and all other heddles are lowered. A shot of weft 57 is taken in the shed beneath binder warp 50 and above all other warps. The beat of reed 55 on the weft completes the third step.

In the fourth step shown in Figure 26, lingoe heddles 41² are fully raised as the pattern may require, lingoe heddles 41³, binder warp heddle 53 and stuffer warp heddle 47 are raised half way and binder warp heddle 54 is lowered. A wire 58 is inserted in the shed beneath the pile ends of pile warp 40 which are raised by lingoe heddles 41² and above all other warps, while a shot of weft 57 is taken in the shed above binder warp 50 and beneath all other warps. The beat of reed 55 on the wire and weft completes the fourth step and completes the cycle.

Figure 27 illustrates the weave of Figures 23 to 26 in a form similar to that of Figure 6, while Figure 28 shows a condition similar to Figure 9 in which there are high wavy pile loops 63 and low wavy pile loops 63' in the background in one transverse row and high wavy pile tufts 68 and low wavy tufts 68' behind them in the next transverse row. Figure 29 is similar to Figure 28 except that it shows the condition at the pattern change, in which pile warp 40 which has been in the pile toward the left moves to the back and pile warp 40' moves to the front to form wavy pile tufts 68 and loops 63 in alternate transverse rows.

Figure 30 shows the conventional Wilton carpet diagram with front and back wefts separated in accordance with Figure 28, wavy pile loops 63 being of varying heights in the same transverse row and wavy pile tufts 68 in the alternate transverse rows likewise being of varying height in the same row.

It will be evident that the principles of the invention can be applied to varying pile carpet weaves in addition to those already described.

When warp is used herein, it is intended to designate a group of similar warp ends side by side.

A cycle as defined herein is one series of shedding procedures extending until the shedding procedure repeats.

In view of my invention and disclosure variations and modifications to meet individual whim or particular need will doubtless become evident to others skilled in the art, to obtain all or part of the benefits of my invention without copying the process and fabric shown, and I, therefore, claim all such insofar as they fall within the reasonable spirit and scope of my claims.

Having thus described my invention what I claim as new and desire to secure by Letters Patent is:

1. The process of weaving a pile carpet, which comprises interweaving at least one pile warp, stuffer warp ends, binder warp ends and wefts into a close woven fabric having in excess of seven rows of pile projections per inch, alternately raising the same pile warp in weaving over a straight non-cutting pile wire and then over a pile wire having high and low portions within the shed and having a cutter at the far end, withdrawing the wires while cutting the pile warp by the wire having the cutter, and during withdrawal of the wires pulling down the uncut loops formed over the straight wire by the wire having high and low portions within the shed, and restricting such pull-down by virtue of the tightness of weave resulting from the above close weaving and thereby building up stress in the fabric to cause the tufts formed at both sides by cutting the loops through the action of the wire having the cutter to have high and low portions in the same transverse row, whereby both the uncut loops and both sets of cut tufts have high and low portions in the same transverse row.
2. The process of weaving according to claim 1, which comprises weaving to a closeness between seven and twelve wires per inch.
3. The process of weaving according to claim 1, which comprises weaving over a straight non-cutting pile wire and over a wire having high and low portions within the shed of maximum height substantially equal to the height of the straight non-cutting pile wire and having a cutter at the far end, and masking the pile loops by the pile tufts at certain intervals along the transverse rows.
4. The process of weaving according to claim 1, which comprises raising all ends of the pile warp at different positions in each cycle over both wires.
5. The process of weaving according to claim 1, which comprises interweaving a plurality of pile warp sets.
6. The process according to claim 1, which comprises interweaving a plurality of pile warp sets and making pattern selection of individual pile warp ends.
